Patented Mar. 14, 1961

189,887

IRON

Melvin H. Boldt, Glenview, Ill., assignor to National Presto Industries, Inc., Eau Claire, Wis., a corporation of Wisconsin

Filed May 4, 1959, Ser. No. 55,755

Term of patent 14 years

(Cl. D49—6)

FIG. 1

FIG. 2

FIG. 3

FIG. 4

Figure 1 is a top view of an iron showing my new design;

Fig. 2 is a front perspective view thereof;

Fig. 3 is a rear perspective view thereof; and

Figure 4 is a bottom plan view thereof.

The dominant features of the design reside in the portions shown in full lines.

I claim:

The ornamental design for an iron, substantially as shown and described.
